UNITED STATES PATENT OFFICE.

WALLACE B. WOLFF, OF CHICAGO, ILLINOIS, ASSIGNOR TO AMERICAN SLICING MACHINE COMPANY, OF CHICAGO, ILLINOIS, A CORPORATION OF NEW YORK.

SLICING MACHINE.

Application filed April 13, 1928. Serial No. 269,705.

My invention relates to a slicing machine and particularly to a slicing machine having a rotary knife and means for driving it, of the type wherein a work supporting carriage is provided and means for guiding it across the face of the knife. One object of my invention is to furnish a support for the slices which are being cut. The presence of such a support, which holds the slice in the plane of the larger piece from which it is cut, insures a uniform and efficient severance of the slices from the piece, prevents ragged slices, and prevents slices from being partially severed. A clear, complete cut is insured. Another object of my invention is to prevent the slices from falling into the space between the gauge plate and the carriage, and to insure that each slice cut shall pass through the space between gauge plate and knife to the trough or receiving means. Other objects will appear from time to time in the course of the specification and claims.

I illustrate my invention more or less diagrammatically in the accompanying drawings, wherein—

Figure 1 is a front elevation;

Figure 2 is a section on the line 2—2 of Figure 1;

Figure 3 is a section on line 3—3 of Figure 2; and

Figure 4 is a detail.

Like parts are indicated by like symbols throughout the specification and drawings.

A indicates any suitable slicing machine base member having the ground engaging supports or studs A¹. B generally indicates any suitable housing member or body upwardly projecting therefrom having associated therewith a face plate B¹, normally fixed in position and a gauge plate B² which may be moved toward and away from the plane of the knife as for example by rotation of the knob B³. I do not wish to be limited to any particular means for imparting movement to the gauge plate but I have herein shown lugs B⁴ on the rear of the gauge plate, levers or arms B⁵ pivoted thereto, themselves pivoted as at B⁶, a gear B⁷ associated with one of said levers and a worm B⁸, in mesh therewith and actuated by the knob B³.

C indicates the knife, it being herein shown as recessed in its forward face as at C¹ in order to permit the peripheral portion C² to project outwardly into and slightly beyond the planes of the face plate B¹. It will

be understood that the axis of the knife, in the form herein shown, lies in a generally horizontal plane but is tilted slightly from perpendicularity to the face plate B¹, in order to throw one edge of the knife forwardly into the plane of said face plate.

D generally indicates a guide track, herein shown as cylindrical, and mounted at its ends upon the supports D¹. Beneath it is a supplemental track D² herein shown as of rectangular cross-section. D³ indicates a carriage slidable along the track D, provided with a downward extension D⁴ formed to surround the track D² and thus to prevent rotation of the carriage D³ about the track D. D⁵ is any suitable manual handle whereby the carriage may be moved along the track D. D⁶ is any suitable material carrying tray positioned upon the carriage D³. Unless the gauge plate B² is adjusted so far forward as to lie practically in the plane of the cutting edge of the knife C there will be a space between the gauge plate and the carriage plate D⁶. If this space is left open, bits or slices of material may under some circumstances drop therethrough instead of passing through the space between the knife edge C² and the opposed arcuate edge of the gauge plate. In order to render this impossible and to insure that all slices shall pass through such gap I provide a supplemental horizontal ledge or plane surfaced member, to prevent such slices from dropping down between the gauge plate B² and the carrier plate D⁶.

As shown for example in Figure 3 I illustrate this member as a flat horizontal shelf E with an inward extension E¹ which may be mounted for example upon any suitable support E² upon the frame of the machine. E³ is an extension to the right, as shown in Figures 2 and 4, which is cut away or formed as at E⁴ in order to hug the rear of the peripheral portion C² of the knife. The portion E proper is aligned with a horizontal slot or aperture E⁵ in the face plate in such fashion that the face plate may be freely adjusted. The gap between the edge of the plate E and the carrier plate D⁶ is so thin that no fragment or slice of material of any substantial thickness can pass therethrough. Preferably the upper level of the shelf E is at the same height or even slightly higher than the top of the plate D⁶.

For example, as shown in Figures 2 and 4, I may make a shelf member E adjustable to

ward and away from the knife edge, as by the employment of the slots E⁶ through which pass the locking or adjusting screws E⁷.

It will be realized that whereas I have described and shown a practical and operative device, nevertheless many changes might be made in size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In employing a meat or work carriage for supporting the carriage for supporting the work as it is carried across the face of the knife, and in employing the gauge plate against which the work is thrust, whether manually or mechanically, it is important to support the slice while the slice is being cut. Were it possible, which it is not, to have the carriage approach so close to the gauge plate that no interval is left between gauge plate and carriage, there will be no necessity of supporting the slice in the front of the gauge plate. However the mere fact that the gauge plate is adjusted toward and away from the path of the carriage insures that there will be a space between gauge plate and carriage. And furthermore, the increase of the opening between the edge of the gauge plate and the cutting edge of the knife, which determines the thickness of the slice, insures that there will always be a space between carriage, gauge plate and knife at that point, in which the carriage gives no support. I therefore provide a shelf or support which cooperates with the carriage and which is independent, in its supporting function, of the position of the gauge plate.

Referring to Figures 2 and 3 it will be clear that the shelf E very closely approaches the edge of the carriage, irrespective of the position of the gauge plate, the gauge plate of course being slotted to permit the passage of the shelf E therethrough. Therefore no slice or fragment of meat can drop down through the space between the carriage and gauge plate.

Even more important is the lateral extension E⁴ of the shelf E, which is formed to hug the cutting edge of the knife. This insures that the slice, in course of severance, will be supported up to the instant of its completion.

The support at this point prevents partially completed slices and little tail ends of meat from sliding down around the corner of the gauge plate and getting between the front of the carriage and the knife.

In view of the frequent practice of using vitreous enamel for carriage and gauge plate the addition of the slice supporting shelf is

important. The front of the carriage is necessarily rounded or oval shaped owing to the fact that the enamel will not stick on a sharp corner. This rounding of the parts would tend to provide an opportunity for the escape of small bits of meat, partly completed slices and the like were it not for the employment of the shelf or support.

Also, the shelf, positioned as it is across substantially the entire front of the gauge plate prevents the last slice from falling down between the front of the carriage and the gauge plate.

I claim:

1. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member outwardly projecting from the plane of said gauge plate toward said carriage and supporting means therefor independent of said gauge plate. 90

2. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member outwardly projecting from the plane of said gauge plate toward said carriage, said gauge plate being 95 slotted to permit the projection of said shelf therethrough.

3. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member outwardly projecting from the plane of said gauge plate toward said carriage and supporting means therefor independent of said gauge plate, the edge of said shelf member closely approaching the edge of said carriage and lying in a 115 plane generally parallel with the plane of the carriage edge and its path of movement.

4. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member outwardly projecting from the plane of said gauge plate toward said carriage and supporting means therefor independent of said gauge plate, and a lateral extension from said shelf member conforming closely to the edge of said knife. 130

5. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member outwardly projecting from the plane of said gauge plate toward 5 said carriage and supporting means therefor independent of said gauge plate, a lateral extension from said shelf member conforming closely to the edge of said knife, and hugging the rear face of said knife.
- 10 6. In a slicing machine having a rotary knife and means for rotating it, a carriage and means for guiding it along a path across the plane of said knife, a gauge plate lying in a plane generally parallel with the path 10 of movement of said carriage, and means for moving it toward and away from said carriage, and a shelf member outwardly project-
- 15 ing from the plane of said gauge plate toward said carriage and supporting means therefor independent of said gauge plate, and means 25 for adjusting said shelf member in a horizontal plane.
7. In a slicing machine having a rotary knife and means for rotating it, a carriage and means for guiding it along a path across 30 the plane of said knife, a gauge plate lying in a plane generally parallel with the path of movement of said carriage, and means for moving it toward and away from said carriage, and a shelf member outwardly projecting 35 from the plane of said gauge plate toward said carriage and supporting means therefor independent of said gauge plate, and means for adjusting said shelf member toward and away from the edge of the knife. 40

Signed at Chicago, county of Cook, and State of Illinois, this 23rd day of March, 1928.

WALLACE B. WOLFF.
